UNITED STATES PATENT OFFICE.

ROBERT C. DANLEY, OF MACOMB, ILLINOIS.

DESIGN FOR A TRACE-SUPPORTER.

SPECIFICATION forming part of Design No. 27,302, dated July 6, 1897.

Application filed January 18, 1897. Serial No. 619,699. Term of patent 7 years.

To all whom it may concern:

Be it known that I, ROBERT C. DANLEY, residing in Macomb, in the county of McDonough and State of Illinois, have invented and produced a new and original Design for Trace-Supporters, of which the following is a specification, reference being had to the accompanying drawings, forming part thereof.

Figure 1 is a front view of a trace-supporter, showing my new design. Fig. 2 is a side view of the same.

As shown in the drawings, the leading or material feature of my design consists of a concavo-concave base *a*, the lateral portion *b* disposed or arranged as shown in Fig. 1, said lateral portion *b* extending downward and at an obtuse angle lengthwise of base *a*,

uniting with cross-bars *c*, as shown in Figs. 1 and 2. The curvated braces *f* unite near the ends of the base *a*, as shown in Figs. 1 and 2. The surface of the brace being left plain, that portion may, it is manifest, be polished or otherwise ornamented, as desired; also a pin *e*, projecting upward from one of the cross-bars *c*.

Having described my invention, what I claim as new, and desire to secure by Letters Patent, is—

The design for a trace-supporter as herein shown and described.

ROBERT C. DANLEY.
